UNITED STATES PATENT OFFICE.

ISAAC B. INGLE, OF BLOOMINGTON, ILLINOIS.

WINDOW-VENTILATOR.

1,204,158.

Specification of Letters Patent. Patented Nov. 7, 1916.

Application filed June 30, 1915. Serial No. 37,213.

To all whom it may concern:

Be it known that I, ISAAC B. INGLE, a citizen of the United States, residing at Bloomington, in the county of McLean and State 5 of Illinois, have invented certain new and useful Improvements in Window-Ventilators, of which the following is a specification.

This invention relates to window ventila- 10 tors, and one of its objects is to provide a ventilator attachment for the window sashes of houses, railway passenger coaches, etc., which will permit free ventilation to any degree desired without opening the sash, and 15 which will prevent the entrance of dust, cinders and other foreign substances.

A further object of the invention is to provide a window ventilator which may be adjusted to regulate the admission of air to 20 the interior of the room or car, which is designed effectually to prevent draft arising from sudden gusts of air passing into the room or car, and which embodies means for further regulating the aggregate size of the 25 air inlet to govern the volume of air admitted into the apartment.

A still further object of the invention is to provide a ventilator which is proof against the entrance of rain or snow, which 30 permits of the ready drainage off of all moisture, and which may be applied or embodied with equal facility in old or new windows.

The invention consists in the features of 35 construction, combination and arrangement of parts hereinafter more fully described and claimed, reference being had to the accompanying drawings, wherein—

Figure 1 is a vertical front-to-rear section 40 through a portion of a window frame and the lower sash, showing the invention applied and embodied in the sash as part thereof; Fig. 2 is a sectional plan view through the part shown in Fig. 1, the plane of section being on a line above the ventilator and showing the lid or cover of the ventilator casing thrown open; Fig. 3 is a view similar to Fig. 2, showing the lid or door of the 45 ventilator casing closed; Fig. 4 is a view similar to Fig. 1, showing the ventilator in the form of an attachment to the lower sash; Fig. 5 is an exterior elevational view of the sash and ventilator shown in Fig. 4.

Referring more particularly to Figs. 1 to 55 3, of the drawings, 1 designates a window frame, of the ordinary or any preferred con-

struction, and 2 the lower sash, which, when in closed position is adapted to rest against the base or sill 3 of the window frame. As shown in these views, the ventilator forms a part of the base or bottom rail of the sash 2 and includes a box or casing 4 extending horizontally across the base of the sash, upon the inner side thereof, and having in the form shown a hinged lid or cover 5 provided with one or more air inlets or ventilation openings 6, preferably covered by screen gauze 7 in order to prevent the admission of dust, cinders and other foreign particles. The lid may be dispensed with and a rigid top substituted therefor, but when a lid is employed the said lid is provided with a suitable knob or finger piece 8 whereby it may be conveniently opened and closed. When the lid is closed, the amount of air admitted is governed entirely by the aggregate area of the inlets 6, but if the admission of a greater volume of air be desired the lid may be thrown back to an open position, thus entirely uncovering the opening at the top of the casing for the admission of air. Fixed to the top of the lid or cover is a flanged metallic frame 9 having upstanding portions 10 forming guideways for one or more sliding dampers or cover plates 11 which may be adjusted to restrict the size of the inlets 6 to decrease the amount of air admitted to the room or apartment or to cut off entirely the entrance of air as desired. The guideways formed by this metallic strip have end portions 12 which serve as guards and prevent the removal of the sliding dampers 11, thus preventing their detachment by children or malicious persons.

The outer side of the casing is formed by the bottom rail 13 of the sash, as part thereof, which rail may, therefore, be made of somewhat greater depth or vertical extent than is usual. The rail is provided with a longitudinally extending opening 14, which is of a length substantially equivalent to the casing 4 and provides for the free admission of air to the interior of said casing. As shown, the bottom 15 of the casing is inclined or sloped outwardly and downwardly to permit of the drainage off of all moisture, while the upper wall of the opening 14 is beveled or inclined upwardly and inwardly, as indicated at 16, to increase the size of the opening 14 inwardly of its entrance, thus allowing air freely to pass to the top of the casing, while at the same time diminishing

the size of the entrance side of the opening 14 in such a manner as to prevent snow from being blown into the casing and through the inlets 6 into the car and lodging in and choking up the casing. The beveled surface 16 furthermore gradually restricts the size of the passage leading from the opening 14 to the inlet 6, thus preventing sudden drafts of air from passing through the inlets into the 10 room or apartment.

It will be evident from the foregoing description that as the ventilator forms a part of the base of the sash, the sash may be kept entirely closed, while at the same time free 15 ventilation of the room or apartment through the sash may be permitted in such a way as to protect the occupants of the room from dust, cinders, dirt, snow, rain and drafts, and ample ventilation may be obtained without the necessity of opening the 20 window, and while the window may be held fastened or locked in closed position, as during the night time. In order to govern the supply of air through the ventilator, and 25 further diminish the liability of the forcible entrance of air, I provide an adjustable damper 17 in the flaring passage leading to the inlets 6. This damper preferably consists of a block of wood or other suitable 30 material, of triangular form in cross section, and having pins or reduced portions 18 at its ends to pivotally and removably engage grooves 19 in the end walls of the casing 4, whereby the damper block is pivotally and 35 removably mounted. The block may be turned to different positions, so as to present its base or broad side either upwardly or downwardly to vary the size of the passage. If at any time it should be desired to secure 40 the fullest ventilation possible, the block may be removed by simply sliding it upward out of the grooves and as readily replaced again for use by simply fitting it down into the grooves, as will be readily understood.

In the form of my invention shown in Figs. 4 and 5, the construction of the ventilator casing and base board or bottom rail 13' is the same as the board or rail 13 previously 50 described, except that instead of forming a part of the bottom rail 20 of the sash 2 it is arranged beneath the bottom rail of the sash and secured thereto by suitable fastening brackets 21. The construction of 55 the ventilator is otherwise the same as that previously described. In both constructions, it will be evident that the ventilator comprises a base board or rail having an admission opening of the character defined there- 60 in, and a casing upon the inner side of the board or rail constructed and operating as described, whereby the device is adapted to be built in as a part of the base or sash or may be applied as an attachment to a sash 65 already in use, in which latter event a por-

tion of the sash rail may or may not be cut off, as desired.

One advantage of my invention is that the ventilator may be built in to form the lower portion of the sash, by simply disposing the lower cross bar of the sash at an elevation between the side bars of the sash, and then disposing the ventilator in position between the lower extensions of the side bars thus produced. The upper portion of the 75 sash may then be closed in the usual way, while the lower portion provides a ventilator, and this sash may be of any stock size and adapted to be opened and closed and fastened in the usual way. 80

I claim as my invention:

1. A window ventilator comprising a board or rail having an air inlet opening extending therethrough, a casing upon the inner side of said rail in communication with said opening having inlets above the plane of the opening, and means associated with the upper ends of the inlets for controlling the same, and an angular bar journaled in said casing and removable through 90 the upper end thereof for regulating the passage of air to said openings. 95

2. A ventilator comprising a board or rail having an air inlet opening, a casing upon one side of said rail having an open top 95 above the level of the air inlet opening in the rail, a lid or cover for closing said top, said lid or cover being provided with a ventilation opening, a guideway, a damper movable in said guideway and governing said 100 opening, and an angular bar journaled in said casing and removable through the upper end thereof for regulating the passage of air to said openings. 105

3. A ventilator comprising a board or rail having an air inlet opening, a casing upon one side of said board or rail and having an air passage in its top above the level of the said inlet opening, the top wall of said opening being arranged to slope upwardly 110 and inwardly toward said passage, and a triangular-shaped block journaled in said casing to control the passage of air to said openings. 115

4. A ventilator including a board or rail having an air inlet opening, a casing on one side of said rail having an inlet at its top above the level of the top of said opening, the bottom walls of the rail opening and casing being outwardly and downwardly sloped 120 and the top wall of the opening being upwardly and inwardly sloped, means for controlling the admission of air through the inlet at the top of the casing, the end wall of said casing having slots open at one end 125 thereof, and an angular bar journaled in said slots for regulating the passage of air through the casing to the openings. 130

5. A ventilator including a bar or rail having an opening extending therethrough, 135

a casing upon one side of said rail and communicating with said opening, said casing having an open top above the level of the opening and provided in its end walls with 5 grooves, a lid for closing the open top of the casing and provided with a ventilation passage, a damper for closing said passage, and a triangular bar having reduced projections adapted to engage said grooves, said bar being 10 removably and pivotally supported in

the passage, whereby the bar may be removed or adjusted to different positions to vary the size of the passage.

In testimony whereof I affix my signature in presence of two witnesses.

ISAAC B. INGLE.
